UNITED STATES PATENT OFFICE.

WILLIAM M. KECK, OF COALINGA, CALIFORNIA.

ROTARY DRILL-BIT FOR OIL-WELLS.

1,125,553.

Specification of Letters Patent.

Patented Jan. 19, 1915.

Application filed March 11, 1914. Serial No. 823,935.

To all whom it may concern:

Be it known that I, WILLIAM M. KECK, a citizen of the United States, and a resident of Coalinga, in the county of Fresno and 5 State of California, have invented a new and Improved Rotary Drill-Bit for Oil-Wells, of which the following is a full, clear, and exact description.

This invention relates to deep well boring 10 or drilling apparatus, and has particular reference to means for boring rapidly through various characters of earth or rock.

Among the objects of the invention, more specifically stated, is to provide a drill bit, 15 preferably of the fish tail form, adapted to operate rapidly and without clogging through soft, sticky or shaly rock.

The foregoing and other objects of the invention will hereinafter be more fully described and claimed and illustrated in the 20 drawings forming a part of this specification in which like characters of reference indicate corresponding parts in all the views, and in which—

Figure 1 is a side elevation of a preferred 25 form of the invention; Fig. 2 is a top view of the same; and Fig. 3 is a transverse section on the line 3—3 of Fig. 1.

The several parts of the device may be 30 made of any suitable materials, and the relative sizes and proportions, as well as the general design of the mechanism, may be varied to a considerable extent without departing from the spirit of the invention 35 hereinafter more fully set forth and specifically claimed.

I show at 10 a drill bit of the fishtail type 40 having cutting edges or points 11 at its lower end. At the upper end I provide a shank 12 having one or more, shown as two, diagonally arranged bores 13 extending from the top thereof downwardly into the side wings 14 of the bit. Said shank is provided with a screw thread for connection 45 with the drill stem (not shown) and through which water or other suitable fluid is forced downwardly into and through said bores 13.

The drill bit is adapted to be rotated in 50 the direction of the arrow, Fig. 2, and upon

the advancing face of each wing 14 is arranged a tubular discharge means for the water conveyed through the corresponding bore 13. Said means comprises a tube 15 preferably cast integrally upon said advancing face and providing a bore 15' communicating with the lower end of the adjacent bore 13. The lower open end of the tube 15 is located at a suitable distance above the cutting edge 11 of said wing, two purposes 60 being subserved by such arrangement; first, water forced downwardly through the bores 13 and 15' will be discharged directly upon the active face of the wing serving to keep such wing flushed clean with respect to any 65 accumulation of sticky earth or rock which would tend to clog up the device, and secondly, by locating the end of the tube at some distance above the cutting edge 11, I am enabled to resharpen the drill as may 70 be required without interfering with the function or action of the water tube mechanism.

I am aware that it has been proposed heretofore in devices of this general character to deliver a stream of water along the center of a drill bit, but such arrangement can not be depended upon for the most expeditious and satisfactory operation in all kinds of earth and rock which are repeatedly 80 being encountered in deep well operations.

Having thus described my invention, I claim as new and desire to secure by Letters Patent:—

1. In a device of the character set forth, 85 a deep well drill bit including a shank and a pair of laterally projecting wings terminating in cutting edges, said drill bit being provided with means to deliver water under force diagonally through the stem and deliver it upon the advancing face of each wing above the lower cutting edge thereof whereby said face is kept flushed clean of sticky material.

2. The herein described deep well drill 95 bit comprising a shank and integral wings terminating in cutting edges, said shank being provided with diagonally arranged bores leading from the upper end of the shank downwardly and laterally into said 100

wings, the advancing face of each wing being provided with an integral tubular member having a vertical bore constituting a continuation of the adjacent diagonal shank bore, the lower end of the tubular member being located above the cutting edge of such wing.

In testimony whereof I have signed my name to this specification in the presence of two subscribing witnesses.

WILLIAM M. KECK.
